[57] CLAIM

The ornamental design for a folding and smoothing
machine for skirts and the like, substantially as shown.

DESCRIPTION

FIG. 1 is a front view of a folding and smoothing
machine for skirts and the like embodying my new design;
FIG. 2 is a bottom view of the machine shown in FIG.
1;

FIG. 3 is a back view of the machine shown in FIG. 1;
FIG. 4 is a top view of the machine shown in FIG. 3;
FIG. 5 is a view of the lefthand end of the machine
shown in FIG. 3;

FIG. 6 is a view of the righthand end of the machine
shown in FIG. 3; and

FIG. 7 is a perspective view looking toward the right
front corner of the machine in FIG. 1.
